UNITED STATES PATENT OFFICE

ATHENA J. ENGLISH, OF CHICAGO, ILLINOIS, ASSIGNOR OF ONE-HALF TO SOTIR C. STAMOULIS, OF CHICAGO, ILLINOIS

CLEANING COMPOUND

No Drawing.

Application filed April 30, 1929. Serial No. 359,408.

My invention relates to improvements in fabric treating preparations generally, and has for its primary object the provision of a preparation which will remove the gloss or shine from fabric,—particularly trousers and the like.

It is a well known fact that after a considerable period of use trousers develop a "shine" produced by a wearing-off of the nap of the cloth. The up-shot of this situation is that the garment has to be cast aside by the particular dresser long before it is worn out.

While the primary object of this invention is to remove this gloss or shine,—yet it is also an object of the invention to provide in the preparation cleaning properties in addition.

The invention further contemplates a preparation of the character specified which is very inexpensive, easy to compound and which will not spot, discolor or otherwise injure the fabric,—and further one which is non-inflammable, non-poisonous and non-injurious to the person of the wearer.

The invention also resides in the method of compounding the preparation and in certain novel features of combination of the elements of the composition and in the elements themselves, all of which will be readily understood and appreciated by those skilled in the art upon reference to the following detailed descriptive matter.

In carrying out the invention the following ingredients are used:

25 Irish potatoes-----1 pound.
Water-----1 quart.

The preferred mode of compounding the preparation may be described as follows:

First the potatoes are peeled, after which they are washed and dried with a cloth. Next the potatoes are sliced into small pieces or squares of about $\frac{1}{4}$ inch size. The potatoes cut up, as mentioned, are poured into a vessel containing the quart of cold water. The vessel must be covered to protect the liquid from dust or dirt. To secure the best results the vessel in which the potatoes are placed should be enamel or the like, as a bare metal vessel tends to give off matter which

is absorbed by the preparation. The potatoes are allowed to stand in the water for 20 hours. However, approximately every 2 hours the potatoes should be mixed or crunched with the hand, the best results being obtained by stirring the potatoes in addition to the crunching thereof, just referred to.

At the end of the 20 hour period indicated, the water will have assumed a very dark brownish color,—rather closely approaching black. This is poured off into bottles or vessels and the remnants of the potatoes thrown away. The resultant liquid which is poured off is the cleaning preparation.

Same results can be obtained by allowing the potatoes in the water to stand still for 36 hours without any crunching with the hand.

The application of this resultant liquid to the goods is made by means of a stiff brush, the liquid being poured into a pan and a brush frequently dipped thereinto so that the garment, spread upon a flat surface, preferably a glass ironing board, may be well saturated with the liquid. The brush is preferably a rather stiff brush having horse-hair bristles,—although other types of stiff brushes can be used satisfactorily. The garment is rubbed briskly with the liquid saturated stiff brush for about two and one-half minutes. When first commencing the rubbing operation, a slight white foam will appear upon the garment. The brush should be dipped into the cleansing liquid often enough to keep the said foam present for about two and one-half minutes of brisk rubbing. At the completion of the period referred to, the garment will be given one or two brisk rubs to make sure that the foam, at the surface of the garment, has been removed after which the garment will be allowed to dry and then pressed. The shine surface will be completely eliminated and will not return, although of course, the wearer after a month or so of use of the suit will redevelop a shine surface.

Sometimes a garment gets shiny from neglect of tailor leaving iron or pressing machine long time on, then suit or garment does not require cleaning, but simply removal of the shine only.

Referring to the cleaning liquid, it is to be observed that when it is allowed to stand there settles in the bottom a white cloudy substance of a depth of about $\frac{3}{8}$ of an inch in a half-pint flask. Above this white cloudy substance is a much darker substance occupying a depth in a half-pint flask of approximately $\frac{3}{4}$ of an inch. Above this is a rather darkened liquid.

- 10 It is to be observed that the potatoes while soaking in the cold water in the pot or vessel gradually turn slightly reddish, then lavender, and finally black, indicating that there is considerable decomposition of the potatoes 15 during the 20 hour soaking period. The stirring or mixing of the potatoes, every 2 hours, as specified, serves to impregnate the water with the products given off by the decomposition of the potato fragments.

- 20 Analysis of a quart of the composition discloses the following:

Protein (nitrogen X 6. ²⁵)-----	0.37%
Ash (mineral matter)-----	0.25%
25 Reducing sugars as dextrose-----	0.13%
Other carbohydrates and a little fibre-----	0.10%
Total solids-----	0.85%
30 Water-----	99.15%
Total-----	100.00%
Total nitrogen-----	0.59%
Amide nitrogen-----	0.36%

- 35 For preservative purposes I may add a small quantity of sodium benzoate,—say one-eighth ($\frac{1}{8}$) oz. by weight to a quart of the liquid.

- 40 By a litmus paper test of the liquid slight acidity is indicated.

I am aware that some efforts have been made heretofore to evolve a preparation for restoring the nap of fabrics and for removing the shiny surface thereof. However, 45 heretofore a strong acid, such as carbolic, acetic has been used in large quantities, the result is the production of a ring around the area treated or at certain points within the area due to disproportionality of the acid and 50 the alkaline component. No such difficulty attends the use of my composition which may be used upon a part or the whole of a garment without leaving a single blemish thereon.

In my opinion, application of my preparation 55 softens the thread and causes same to swell, thus loosening the fibre which is impregnated to a limited extent with the solid content. The brushing in addition to expediting the action referred to loosens external fibres, producing a new nap.

Having thus described my invention, what I claim as new and desire to secure by Letters Patent is:

1. The method of delustering fabric by 60 friction of the surface after wetting with the

supernatant liquid from a mixture of macerated raw potato and water.

2. The method of removing sheen from worn garments by wetting the sheen surface with a liquid obtained from macerated raw 70 potatoes and water, and briskly rubbing the wetted surface immediately thereafter.

In testimony whereof I affix my signature.
